UNITED STATES PATENT OFFICE.

CHARLES C. HANSEN, OF EASTON PENNSYLVANIA, ASSIGNOR TO INGERSOLL RAND COMPANY, OF NEW YORK, N. Y., A CORPORATION OF NEW JERSEY.

DRILL.

1,113,620.

Specification of Letters Patent. Patented Oct. 13, 1914.

Application filed April 23, 1912. Serial No. 692,745.

To all whom it may concern:

Be it known that I, CHARLES C. HANSEN, a citizen of the United States, and resident of Easton, in the county of Northampton and State of Pennsylvania, have invented a new and useful Improvement in Drills, of which the following is a specification.

This invention consists in a novel drill structure in which the drill steel is provided with a surrounding casing forming between them one or more inclosed channels through which the bored material may be forced from the cutting end of the steel, the channel or channels being utilized for the escape of the cut material and being provided with check valves for preventing the return of the said cut material.

My invention more particularly relates to the particular construction of the valve cage and the tube whereby the valve cage is held in position by the tube.

In the accompanying drawings, Figure 1 represents a cruciform drill steel in side elevation with my invention applied thereto. Fig. 2 is a similar view in a plane at right angles to Fig. 1, the tube being shown in longitudinal central section. Fig. 3 is a longitudinal central section through the drill steel, the tube which surrounds the same and through two oppositely arranged valve cages. Fig. 4 is a transverse section taken in the plane of the line A—A of Fig. 2, looking in the direction of the arrows, and Fig. 5 is a transverse section taken in the plane of the line B—B of Fig. 2, looking in the direction of the arrows.

The drill steel is denoted by 1, which steel may be reciprocated by a drill of any well known or approved construction. This drill steel is herein shown as cruciform in cross section. A tube 2 surrounds the drill steel and extends from a point near the cutting end thereof the desired distance along the drill steel. This tube snugly engages the outer edges of the wings 3, 4, 5, 6, of the drill steel, thereby forming four inclosed channels 7, 8, 9, 10, between the drill steel and the said tube.

Check valves are located in one or more of the inclosed channels for preventing the return of the cut material which may be

forced therethrough. In the present instance I have shown two of these check valves and their cages located in the inclosed channels 8 and 10, leaving the inclosed channels 7 and 9 open for the introduction of water to the cutting end of the drill steel if so desired.

The check valve is shown as a ball valve 11, and its cage comprises a body portion 12 having upper and lower inwardly projecting flanges 13, 14, the lower flange 14 having a passage 15 therethrough which is opened and closed by the ball valve 11. This cage 12 is provided with a raised portion 16 on its outer face, which raised portion is adapted to be inserted into a hole 17 through the wall of the tube 2 for maintaining the cage in position when the parts are assembled.

In assembling the parts, the check valve cages are inserted into the tube 2, with their projections 16 seated within the holes 17. The drill steel is then inserted into the tube, the inwardly projecting flanges 13 and 14 of the cages sliding along within the channels 8 and 10 of the drill steel until the drill steel and tube are brought into the proper position one with respect to the other. To more securely hold the cages in position, the walls of the holes 17 may be hammered down on to the body portions of the cages.

It is evident that various changes might be resorted to in the form, construction and arrangement of the several parts without departing from the spirit and scope of my invention; hence I do not wish to limit myself strictly to the structure herein shown and described, but

What I claim is:

1. A drill steel, a tube surrounding it and forming together therewith a channel, a check valve and its cage located in said channel and means for locking the cage in position comprising a projection on the cage and a hole in the tube for receiving the projection.

2. A drill steel cruciform in cross section, a tube surrounding the steel forming inclosed channels, one or more of said channels being left valveless, a valve or valves

located in the remaining channel or channels, a cage or cages and means for locking the cage or cages in position comprising a projection on each cage and a hole in the tube for receiving said projection.

In testimony, that I claim the foregoing as my invention, I have signed my name in

presence of two witnesses, this nineteenth day of April, 1912.

CHARLES C. HANSEN.
